UNITED STATES PATENT OFFICE

98,160

DESIGN FOR A BELT BUCKLE

Joseph P. Gordon, Rockford, Ill.

Application May 27, 1935, Serial No. 57,046

Term of patent 14 years

To all whom it may concern:

Be it known that I, Joseph P. Gordon, a citizen of the United States, residing at Rockford, in the county of Winnebago and State of Illinois, have invented a new, original, and ornamental Design for a Belt Buckle, of which the following is a specification, reference being had to the accompanying drawing, forming part thereof.

In the drawing—

Figure 1 is a face view of a belt buckle showing my new design. The body of the belt buckle is in the form of a substantially flat coil of spring

wire, and the design is characterized by an effect produced by crimping the convolutions at the face of the coil body.

Fig. 2 is an end view of the belt buckle looking at the end having the loop fastening, and

Fig. 3 is an end view looking at the end having the buckle fastening.

I claim:

The ornamental design for a belt buckle, substantially as shown and described.

JOSEPH P. GORDON.
